HAIR CURLING DEVICE

Richard Klein, Detroit, and Joseph Bodnar,
Wyandotte, Mich.

Application August 20, 1932, Serial No. 629,566

10 Claims. (Cl. 132—36)

Our invention relates to a new and useful improvement in a hair curling device and has for its object the provision of a hair curler embodying a curling prong supported on retaining discs and while rigidly mounted thereon also rotatable so that the strand of hair curled upon the prong may, at the proper time, in the curling operation, be wound more tightly about the prong.

Another object of the invention is the provision of a curling prong so mounted as to be freely rotatable in one direction and non-rotatable in the other direction.

Another object of the invention is the provision of a device of this class in which a curling prong may be mounted so as to be rotatable in one direction and non-rotatable in the other and its direction of rotation easily and quickly reversed.

Another object of the invention is the provision in a curling device of this class of a pair of relatively movable hair retaining members provided with means for easily and quickly locking these members against relative movement.

Another object of the invention is the provision in connection with a device of this class of a revolving or wrapping ribbon cut diagonally at its ends so as to provide a device whereby an easy and quick wrapping of the curl may be effected.

Another object of the invention is the provision of a curling device adapted for being slidably and rotatably mounted on the curling prong and free from tilting movement when in use.

Another object of the invention is the provision in combination with a heating element for heating a curl of means for indicating the temperature of the heating element.

Another object of the invention is the provision in a curling device of this class of yieldable means for retaining the device in the bore of a heating element.

Other objects will appear hereinafter.

The invention consists in the combination and arrangement of parts hereinafter described and claimed.

The invention will be best understood by the reference to the accompanying drawing which forms a part of this specification and in which,

Fig. 1 is a central vertical sectional view of the invention.

Fig. 2 is a view taken on line 2—2 of Fig. 1.

Fig. 3 is a view taken on line 3—3 of Fig. 1.

Fig. 4 is a view taken on line 4—4 of Fig. 1.

Fig. 5 is a view similar to Fig. 4 showing the locking mechanism reversed.

Fig. 6 is a plan view of the wrapping ribbon used in the invention.

Fig. 7 is a side elevational view of a heating indicator with parts broken away and parts shown in section.

Fig. 8 is a view taken on line 8—8 of Fig. 1.

Fig. 9 is a fragmentary side elevational view taken on line 9—9 of Fig. 1.

The invention embodies a cup-shaped disc having the base 12 and the side wall 13, this side wall 13 being cut away throughout a portion of its length as at 14. Rotatably mounted in the disc so as to rest upon the base 12 is a cup-shaped disc having the base 15 and the side wall 16. A stud 17 is secured to and projects outwardly from the side wall 16 so as to ride in the cut away portion or slot 14. A nut 18 is threaded on the stud 17 and when threaded against the wall 13 will serve to lock these discs in fixed relation to each other.

A rod 19 projects through the base 15 of the inner disc and is fixedly attached to the base 12 of the outer disc. Fixedly mounted on the rod 19 so as to engage the upper face of the base 15 is a head 20 so that the discs will be prevented from moving axially of each other.

Extending upwardly from the head 20 and embracing the rod 19 is a tapered sleeve 21 about which the wisp of hair to be curled is wound. This sleeve 21 is knurled on its periphery adjacent its upper end as at 22 and at its upper end this sleeve is hollowed out to provide a socket 23.

A sleeve 25 is adapted for fitting loosely in the socket 23. The opposite ends of this sleeve 25 are slotted as at 26 and 27 so as to straddle the pin 24 which projects outwardly from the periphery of the rod 19. A curved spring 28 is secured at its end 29 to the sleeve 25 and coiled partially around this sleeve with the free end 30 normally in engagement with the inner surface of the socket 23. A cap or spaced sleeve 31 is held in position over the upper end of the sleeve 25 by means of the nut 32 which is threaded on the upper end of the rod 19. Since the slotted ends of the sleeve 25 straddle the pin 24 it is obvious that the sleeve 25 cannot rotate about the rod 19 which projects therethrough. On account of the engagement of the free end 30 of the spring 28 with the inner surface of the socket 23 the sleeve 21 will be rotated only in one direction around the rod 19.

In the form shown in Fig. 5 it is possible to rotate the sleeve 21 around the rod 19 in a clockwise direction. An attempted reverse rotation would cause the end 30 of the spring to snag against the inner surface of the socket 23 and bind so as to prevent the reverse rotation. When

it is desired to have the sleeve 21 rotated in a reverse direction about the rod 19 the sleeve 25 may be removed and placed in the socket 23 reversed end for end so that the spring 28 would extend 5 in the direction shown in Fig. 4. In such a form the sleeve 21 may be rotated in a counter clockwise movement around the rod 19 but not in a clockwise direction. The removal and replacement of the sleeve 25 is a simple operation as it 10 is but necessary to remove the nut 32 and the cap 31 in order to obtain access to the sleeve 25.

As shown in Fig. 2 the bottom 15 of the inner disc is provided with an inwardly projecting slot 33 and the bottom 12 of the outer disc is provided 15 with a similar slot 34. When these discs are moved to position so that these slots are in alignment the wisp 35 of hair which is to be curled may be engaged and securely locked in position so that the disc bottom 12 is held in closed engagement with the scalp by moving the discs relatively to each other until the wisp of hair is securely clamped in position. These discs may then 20 be locked in this clamping position by tightening the nut 18 on the stud 17.

25 To wind the wisp of hair about the curling prong or sleeve 21 we provide a curler embodying the hook 36 formed from wire which is carried by the resilient metallic sleeve 37 formed by doubling the piece of resilient material upon itself. 30 A screw 38 is provided and is projected through the doubled over end of the carrier 37 and provided with a nut 39 so that its frictional engagement of the sleeve 21 may be regulated. The free ends of this doubled over carrier are curled as at 35 40 to provide enclosures for the reception of the wire ends which are curled to form the winding hook 36. Tongues 41 and 42 are formed on the upper end of this carrier and bent around the sleeve 21 so as to resist a tilting strain which may 40 be transmitted to the carrier 37 when the hair is being wound. When the strand of hair has been firmly wound about the rod or sleeve 31 it may be moistened with a suitable moistening lotion and thereupon a felt washer 43 is pressed 45 downwardly so as to rest on the upper surface of the bottom 13 of the inner disc. A wrapping cloth or ribbon 44 which has previously been saturated with a suitable lotion is then wound around the hair so as to entirely enclose the same. In 50 order to facilitate the enclosing of the wound strand or wisp of hair we have found it desirable to form the winding cloth or ribbon from a body 44 having its ends 45 and 46 cut diagonally so that in winding the diagonal cut is placed parallel with the plane of the disc 15 and the winding proceeded with. When the winding is complete the ribbon will terminate with its other diagonal end lying in a plane parallel to the plane of the disc 13 and the diagonally cut ends form narrow 55 strips which permit of an easy winding and secure binding. When this has been done we provide an enclosing tube 47. The hair is then wound tightly about the sleeve or rod 21 by gripping the knurled portion 22 of the sleeve 21 and rotating it about the rod 19. Its direction of rotation will, of course, have to be in the same direction as the winding of the wisp of hair or strand of hair 35 so as to tighten this strand. Its direction of rotation can be only in this direction if the operator has 60 wound the hair in the right direction dependent upon which end of the sleeve 25 has been placed downwardly. Considerable strain and tension will thus be placed upon the curl and a reverse rotation of the sleeve 21 will be prevented by the 65 free end of the spring 28. The enclosing tube 47

is slipped over the curled and wrapped hair as shown in Fig. 1. This enclosing tube 47 is provided with a flange 48 projecting outwardly from which is a locking tongue 49 which engages the wall 16 of the inner disc when rotated relatively thereto so as to firmly bind the tube 47 in engagement with the gasket or washer 43 and form a steam tight and liquid tight connection so that it is impossible to burn the scalp through the escape of liquid or steam. This enclosing tube 47 is provided with a spring 50 which is attached thereto at one end and free at the other. This spring is bow-shaped intermediate its ends so that when the tube 47 is inserted into the bore 51 of the heating element 52 the spring 50 will serve to prevent its undue removal therefrom.

As carrying on a curling operation it is quite important that the curl be heated to a predetermined temperature. If this temperature is exceeded to any extent a burning of the hair may result and if the temperature is not reached a proper curling of the hair cannot be effected. In a curling machine a number of heating elements are provided and seldom, if ever, are all of these heating elements in use in a single heating 100 operation, but they are all connected to the same source of heat so that the temperature of each is the same. We have provided a heat indicator which may be inserted in one of the idle heat units so that when the proper temperature has been reached this indicator will indicate the same and the operator may then know that the curling operation is completed. This heat indicator comprises a tube 53 preferably filled with a powdered graphite 53' and in which is inserted the lower end of the mercury tube 55 which is supported by the extension 56 of the tube or shell 53. The mercury tube 55 will be suitably graduated to indicate temperature conditions. A spring 54 connected at one end to the tube 53 105 is free at its opposite end and bow-shaped intermediate its ends so as to engage the inner surface of the bore 51 of the heating element 52 and retain the heat indicator in position therein. The upper end 57 of this spring 54 is angularly turned 110 to form an abutment so that a slipping downwardly of the tube 53 for any reason may be prevented. With a curling device of this class a simple and easily operated mechanism is provided and one in which a very desirable type of curl 115 may be accomplished. Safety is also afforded in that a leak of liquid or steam against the scalp is avoided and due to the use of the heat indicator described the proper temperature will always be arrived at.

120 While we have illustrated and described the preferred form of our invention we do not wish to limit ourselves to the precise details of structure shown, but desire to avail ourselves of such variations and modifications as may come with- 125 in the scope of the appended claims.

Having thus described our invention, what we claim as new and desire to secure by Letters Patent is:

1. In a hair curling device of the class de- 140 scribed: a rotatable prong about which hair may be twined; a supporting member for supporting said prong and permitting rotation of the same; and means for preventing rotation of said prong in one direction while freely permitting rotation 145 of the same in the other direction, said means being reversible for permitting free rotation of said prong in the reversed direction and preventing rotation of the same in the original direction.

2. In a hair curling device of the class de- 150

- scribed: a tubular prong about which hair may be twined; a supporting rod extended through said prong; and means for preventing rotation of said prong about said rod in one direction and permitting its free rotation about said rod in the opposite direction, said means being reversible for determining the direction of rotation of said prong about said rod. 80
3. In a hair curling device of the class described: a prong about which hair may be wound; an enclosure for said prong adapted for insertion into the bore of a heating element; and yieldable means carried by said enclosure for resisting undue removal of the same from the heating element. 85
4. In a hair curling device of the class described: a prong about which hair may be wound; a disc carried by said prong; a cover for said prong engaged at one end with said disc and secured thereto, said cover being adapted for reception into the bore of a heating element; and yieldable means engageable between said cover and the bore of the heating element for resisting undue removal of the cover therefrom. 90
5. In a hair curling device of the class described: a hair receiving member about which hair may be wound; an outer cup shaped disc carried by said member; an inner cup shaped disc positioned within and snugly engaging and rotatable relatively to said first mentioned disc; a stud carried by said inner disc and projecting through a cut away portion of said outer disc; and a nut threaded on said stud and locking said discs in fixed relation to each other. 100
6. In a hair curling device of the class described: a cup shaped disc; a rod secured to and projecting centrally upwardly from said cup shaped disc; a sleeve embracing said rod and adapted for reception of hair to be wound thereon; an inner cup shaped disc positioned within and rotatable about said first mentioned disc concentrically; a threaded member carried by said inner disc; and means threadable on said threadable member for engaging said outer disc for locking said discs in fixed relation to each other. 110
7. In a hair curling device of the class described: a hair receiving prong adapted for reception of hair to be wound thereon; a supporting member for said prong, said prong being rotatable relatively to said supporting member; and means associated with said supporting member for resisting rotation of said prong relatively thereto in one direction while permitting free rotation of the same in the other direction, said means being reversible for determining the direction of rotation of said prong. 120
8. In a hair curling device of the class described, a disc; a rod secured to and projecting centrally upwardly from said disc in fixed relation thereto; a sleeve embracing said rod and adapted for reception of hair to be wound thereon, said disc having a hair receiving opening projecting inwardly from its periphery, said sleeve being freely rotatable on said rod in one direction; and means for preventing a rotation of said sleeve relatively to said rod in the reverse direction. 125
9. In a hair curling device of the class described, a disc; a rod secured to and projecting centrally upwardly from said disc in fixed relation thereto; a sleeve embracing said rod and adapted for reception of hair to be wound thereon, said disc having a hair receiving opening projecting inwardly from its periphery, said sleeve being freely rotatable on said rod in one direction; and means for preventing a rotation of said sleeve relatively to said rod in the reverse direction, said means being reversible to determine the direction of rotation of said sleeve about said rod. 130
10. In a hair curling device of the class described, a disc; a rod secured to and projecting centrally upwardly from said disc in fixed relation thereto; a sleeve embracing said rod and adapted for reception of hair to be wound thereon, said sleeve being rotatable on said rod; reversible means associated with said rod and said sleeve and adapted, when in one position, for preventing relative rotation of said sleeve and said rod in one direction, and when in another position, preventing relative rotation of said sleeve and said rod in the other direction. 135
